DESIGN FOR A COTTAGE

Bernard J. McGarry, New York, N. Y.

Application July 16, 1938, Serial No. 78,544

Term of patent 7 years

To all whom it may concern:

Be it known that I, Bernard J. McGarry, a citizen of the United States, residing in the borough of Manhattan, city, county, and State of New York, have invented a new, original, and ornamental Design for Cottages, of which the following is a specification, reference being had to the accompanying drawing, forming a part thereof, in which:

Fig. 1 is a perspective view of a cottage showing my new design;

Fig. 2 is a side elevational view thereof;

Fig. 3 is a front view; and

Fig. 4 is a rear view.

I claim:

The ornamental design for a cottage, as shown.

BERNARD J. MCGARRY.
